UNITED STATES PATENT OFFICE.

ELIZABETH A. M. GALLAGHER, OF NEW YORK, N. Y.

COLLAPSIBLE BATH-TUB.

1,072,446.

Specification of Letters Patent.

Patented Sept. 9, 1913.

Application filed November 27, 1912. Serial No. 733,837.

To all whom it may concern:

Be it known that I, ELIZABETH A. M. GALLAGHER, a citizen of the United States, residing at New York, in the county of New York and State of New York, have invented certain new and useful Improvements in Collapsible Bath-Tubs, of which the following is a specification, reference being had therein to the accompanying drawings.

10 My invention relates to a new and improved collapsible bath tub, its object being, among other things, to provide a bath tub that is made with a plurality of separable parts that may be conveniently assembled or taken down when desired.

To these, and other ends, my invention consists in the collapsible bath tub, having certain details of construction and combinations of parts, as will be hereinafter described and more particularly pointed out in the claims.

Referring to the drawings, in which like numerals of reference designate like parts in the several figures; Figure 1 is a plan view 25 of the tub frame in its flat position; Fig. 2 is a perspective view of one of the sections; Fig. 3 is a side elevation of the tub complete; and Fig. 4 is a sectional view thereof, taken upon line A—B of Fig. 1 when the frame is 30 assembled.

In the practice of my invention, I provide a plurality of sections, preferably of sheet metal, which are hinged together and capable of being locked when assembled, or 35 folded one against the other when knocked down, so as to occupy the minimum space, and to insert within the frame, when assembled, a rubber lining, which is readily attached and detached as desired.

40 In the drawings, the sections are severally designated 1, 2, 3, 4, 5, 6, 7 and 8. Sections 1 and 5 combine to form the base of the tub. Sections 2, 3, 6 and 8 form the sides of the tub, and sections 4 and 7 the ends. Sections 2 and 3 are permanently 45 hinged to section 1, and when folded, one section lies upon the top of section 1 and the other upon the underside thereof. Sections 4 and 5 are each provided with a pin 9, 50 whereby they are separably hinged to opposite ends of the section 1. Sections 6 and 8 are permanently hinged to the opposite sides of section 5 and fold against said section upon the top and bottom thereof respectively. Section 7 is also provided with a pin 10 and is separably connected with sec-

tion 5 in the same manner as sections 4 and 5 are connected with section 1. Each of the sections forming the sides and ends of the tub are provided with the intermeshing 60 hinged knuckles 11 and 12, which coöperate with the knuckle upon the adjacent section, when in their upright positions, and into which a pin 13 is inserted to lock the several sections together. In Fig. 10 I have 65 only shown two of the pins 13; but it is understood that a pin is required at each corner of the tub in addition to the two shown.

It is apparent that when the several sections are assembled, as shown in Fig. 1, and the side and end sections folded upwardly, and the several pins 13 inserted in the corners of the tub and in the sides, as shown in Fig. 1, that a substantially rigid frame is 75 provided for the rubber lining 14 of the tub, which lies therein and overhangs the rim thereof and is secured by a plurality of fasteners 15 of any preferred form, the details of which are not material to my pres- 80 ent invention.

To break down the tub, the rubber lining is first removed, then all of the pins 13 taken out, and section 7 is then separated from section 5, which in turn is separated from section 1, and upon which sections 6 and 8 are folded upon opposite sides thereof. Section 4 is then removed from section 1, after which sections 2 and 3 are folded upon the top and underside of section 1, as above described. 85 All of the sections now lie flat and are nested compactly together, one upon the other, in which condition they may be inserted in a case or box conveniently designed to receive them.

95 There are numerous devices that may be used to fasten the sections together when in their vertical positions, aside from the pins 13, and I do not therefore desire to be limited to the use of such pins. In many other ways the details of my invention may be modified considerably.

The length of my tub may be varied as desired. By removing the sections 5, 6 and 8 and attaching section 7 to section 1, the tub 105 will be shortened, and to lengthen it, insert as many sections 5, 6 and 8 as are required.

This type of collapsible tub may be used advantageously in houses for maids, where no separate bath room is provided, tenement houses without permanent bath tubs, in hospitals, by travelers, to prevent the spread of

disease, and in many other ways that will readily suggest themselves.

Having described my invention, what I claim as new and desire to secure by Letters 5 Patent, is:—

- 10 1. A bath tub, comprising a frame constructed with a base, composed of a plurality of separably hinged sections; side members hinged to the base sections, each side member composed of a plurality of separable sections; end members separably hinged to the base sections, all of the meeting edges of said sections, not hinged, having interlocking knuckles, and a fastening pin for securing 15 said sections together when said knuckles are interlocked.
- 20 2. A bath tub, comprising a frame constructed with a base, composed of a plurality of separably hinged sections; side members hinged to the base sections, each side member having a plurality of separable sections, the arrangement and connection of

25 said sections being such that one of the base sections and the connected side sections may be removed to shorten the tub, or similar sections added to lengthen the same; and end members hinged to the sections of the base member.

30 3. A bath tub, comprising the hinged base sections 1 and 5; side sections 2 and 3 hinged to the base section 1; side sections 6 and 8 hinged to the base section 5; end sections 4 that are arranged to be hinged to either of the base sections, all of said sections having 35 interlocking knuckles 11 and 12 upon their meeting edges not hinged; and means, as pins 13 that engage said knuckles and lock all of said sections together.

In testimony whereof I affix my signature in presence of two witnesses.

ELIZABETH A. M. GALLAGHER.
